FILM MAGAZINE FOR A MOTION PICTURE
CAMERA OR SIMILAR ARTICLE

Norman R. Kubnick, Wheeling, Ill., assignor to Bell &
Howell Company, Chicago, Ill., a corporation of Illinois

Filed Nov. 14, 1961, Ser. No. 67,513

Term of patent 14 years

(Cl. D61—1)

FIG. 1.

FIG. 2.

FIG. 3.

FIG. 4.

FIG. 5.

FIG. 6.

FIGURE 1 is a front elevation view of a film magazine for a motion picture camera or similar article showing my new design;

FIGURE 2 is a side elevation of the same;

FIGURE 3 is a rear elevation of the film magazine; FIGURE 4 is an elevation of the side opposite that shown in FIGURE 2;

FIGURE 5 is a top view of said film magazine; and

FIGURE 6 is a bottom view of the same.

I claim:

The ornamental design for a film magazine for a motion picture camera or similar article, as shown.
